UNITED STATES PATENT OFFICE.

AUGUST RICHTER, OF NEW YORK, N. Y.

PIANO.

SPECIFICATION forming part of Letters Patent No. 622,783; dated April 11, 1899.

Application filed July 28, 1898. Serial No. 687,097. (No model.)

To all whom it may concern:

Be it known that I, AUGUST RICHTER, a citizen of the United States, residing in the borough of Manhattan, in the city and State of New York, have invented a certain new and useful Improvement in Pianos, of which the following is a specification.

My invention applies to all the varieties of upright pianos, and relates to the provisions for softening the tone which when carried to a great extent is sometimes designated "mute." I employ, as in other mechanisms for this purpose, a movable hammer-rail, which restrains the backward movement of the hammer and is connected to the pedal, so that on depressing the pedal the rail will be moved upward toward the hammers and prevent them from falling back to the limit required for full effect. The reduced movement of the hammers being produced by the same amount of movement of the key as before induces a tendency to lost motion in the key when the soft pedal is in action, so that unless some provision is made for better working the first part of the movement of the key is of no effect and the last part only acts on the hammer-action. Many efforts have been made to overcome this difficulty and to cause the key, and consequently the finger of the player upon the key, to feel the resistance of the action throughout the whole movement of the keys the same as in ordinary playing. One of the modes whereby the lost motion is thus avoided is to shift the relatively-fixed centers of the back ends of the horizontal levers, ordinarily designated "tongues," moving them backward when the soft pedal is depressed. The rods extending upward from the tongues, usually designated "extensions," being correspondingly moved backward and the tongue being now acted upon by the capstan-screw nearer its front end, and consequently farther from its center of motion than before, the tongue will at each depression of the key move through a smaller arc, and there will be a smaller motion of the extension, and consequently the required smaller continuous movement of the hammer. I do this and have devised a new construction of the mechanism by which it is effected: I provide separate pendent links, one for each key, extending downward from

the ordinary transverse or extension rail to the corresponding tongues and operate the whole series of such pendent links and tongues by a single rod mounted below and engaging with a sufficient notch in the lower end of each of such links and moved backward when it is required to make the tone soft. I effect the proper movement backward and forward by a connection from the hammer-rail. What I esteem the preferable form of the mechanism is a double toggle at one side of the piano abutting against a point in front and acting against such rod to urge it backward, and I will describe it as thus applied. The rod is of stout metal and is suspended by a number of hooks or links to points coincident with the axis of the series of separate links which it controls. It performs the duty of shifting all forward and backward without warping or springing.

The accompanying drawings form a part of this specification and represent what I consider the best means for carrying out the invention.

Figure 1 is an elevation of the action. Fig. 2 is a portion of the same, enlarged. Fig. 3 is an enlarged view of the bracket, showing the pedal rod and wire connected to the hammer-rail. Fig. 4 is a portion of the lower rail as viewed from the back. Fig. 5 is a modification.

Similar letters of reference indicate corresponding parts in all the figures where they appear.

A, &c., are fixed portions of the piano, special parts being designated by supernumerals, as A', when necessary. B is the soft-pedal lever, and C is the lifter-rod, sometimes called a "dowel," which rises when the front end of the pedal is depressed by the player and lifts the hammer-rail D, supported and guided in the ordinary manner, thereby restraining the drop of the hammers. These, as also the mechanisms in the vicinity of the hammers—the wippen, &c.—may be of any ordinary or suitable construction.

A' is the ordinary extension-rail.

A² are the ordinary "flanges," screwed firmly upon the rail A' and each carrying a horizontal pivot A³, which serves as the center of motion for one of the pendent links E. The lower end of each link is deeply notched

or forked, the fork being lined with cloth, and receives a single rod of steel G, which latter extends the whole width of the piano mechanism and engages with the whole series of 5 links, so that as the rod is moved backward and forward all the links E and the tongues II, pivoted thereto a little above the forks, are moved forward and backward simultaneously. This rod G, which I will term the 10 "lost-motion" rod, is suspended on hooks G', serving as links, so that it swings from the same axis as the several links E. These hook-links G' are provided one at each end and two at intermediate points. An additional link 15 G², shown at the overhanging end at the base side, is wide and engaged with the operating-toggle. The back face of this link G² is notched to receive the lost-motion rod G. The rod is covered with a piece of soft leather 20 G³ and receives the pressure of a spring F, screwed to the fixed parts above. A double toggle composed of two links I and J, knuckled together at the center, connects this link 25 G² to a pin A⁵, set in the fixed framework.

25 K is a long slender screw adjustable by turning in a flange K', which latter is pivoted at a point in the part J near the central knuckle. The screw K extends up to a lug D' on the hammer-rail D. When the soft 30 pedal B is depressed and operates in the ordinary way through a dowel C to elevate the hammer-rail, the rise of the latter in addition to its ordinary function of restraining the recoil of the hammers by pulling on the wire K 35 partially straightens the toggle—that is to say, it lifts the knuckle joining the parts I and J, with the effect to push the lost-motion rod G rearward, turning on its hooks or links G', and this motion, by reason of the engagement 40 of the several links E with the rod, pulls the links rearward, and thus correspondingly moves the tongues rearward and upward. To these tongues are pivoted the lower ends of the extensions N, sometimes called "sticks," 45 which latter, as also the wippen and entire hammer and damper mechanism operated thereby, may be of any ordinary or suitable character. It will now be seen that the movement of the lost-motion rod G and its connections 50 backward by the partial straightening of the toggle I J moves all the several tongues rearward, and by reason of the rising of the rear end of the tongues as they move backward such movement increases the inclination of 55 the tongues. After such movement backward and such increase of the inclination of their lower faces each tongue continues to raise and lower its extension N with the movements of the respective key in the same manner as before, except that the tongue and its connected actions above now work to a less extent. 60 This is due to the fact that the capstan-screw M' instead of acting under the point under the tongue where it did now acts at a point 65 farther from the center of motion near the front end of the tongue. The capstan-screw has the same amount of motion up and down

as before, but it gives less motion to the extension N, and consequently to the hammer. (Not shown.) The importance of the form 70 and relation of these parts justifies a repetition in different words: It will be observed that the inclined position of the under face of the tongue and the fact that the rear end in the act of being shifted rearward by the depression of the soft pedal B, the raising of the hammer-rail D, and the partial straightening of the toggle I J, is not only moved rearward, but also lifted and raises the extension N, so that before the key is depressed the action is 80 already in contact or close to contact with the hammer in its half-elevated position. Now the depression of the key by raising the extension less, and consequently following the hammer to a less distance than before, is just 85 sufficient to cause the action of the key to be felt on the hammer throughout the whole of its now limited movement. The player finds the resistance to the depression of the keys of the same quality a little less in force, but 90 of the same uniform character as before, being continuous throughout the entire extent of the depression of any key.

When the soft pedal B is released and its front end allowed to rise, its dowel C sinks and allows the hammer-rail D to sink to its ordinary position, thus allowing each hammer to again fall or recoil from the strings to its full extent. The same movement—the downward movement—of the hammer-rail by lowering 100 the wire K allows the toggle I J to again sink into its more folded position, as shown in Fig. 3, and this movement permits the lost-motion rod G, with its train of links E, to swing forward, thus carrying the whole series of tongues II forward again to their ordinary positions. This, by reason of the inclination of the tongues and the fact that this last movement is not only forward but downward, allows each tongue to sink, and consequently causes the extension 105 N to sink back to its original position. Now each key on being depressed acts by its capstan-screw M' at a point nearer the center of motion of the tongue, so as to cause the extension to rise farther by the uniform lifting 110 of the capstan-screw. Consequently the depression of a key causes the action to again follow the hammer to the ordinary full extent, thus giving the full tone to the instrument.

In case there are provisions for adjusting 115 the hammer-rail at intermediate levels, so as to only partially soften the tone, or in case a skilled player with a desire for graduated effects by a guarded movement of his foot depresses the soft pedal only part way, thereby raising the hammer-rail D to only an intermediate position between the full tone and the mute, there will be a closely-corresponding effect produced in changing the connection of the keys to the hammers—that is to 120 say, not only the hammer-rail allows the hammers to fall back each to a position intermediate between the full tone and the mute, but also my mechanism by a lesser straight-

ening of the toggle I J will correspondingly move the several tongues backward to an intermediate position, and the point at which the hammer will be engaged by the action 5 will be correspondingly intermediate, and the extent of the path through which the mechanism will act on the hammer will be correspondingly intermediate. Thus my mechanism allows the obtaining of half or any 10 other desired fraction of the effect of the soft pedal and correspondingly changes the extent of the path through which the action is engaged with the hammer.

None of the parts of my mechanism are 15 liable to be deranged by warping. The rod G and its hooks G' are of metal. The wood in the links E may warp, but such changes in any or all of those separate links will not appreciably influence the relation of any of 20 the parts or appreciably disturb the effect.

Modifications may be made without departing 25 from the principle or sacrificing the advantages of the invention. I can connect the wire K to a point on the part I instead of the part J of the toggle. It is only important 30 that it be near the central knuckle, so as to act with mechanical advantage in changing the annular position of these parts. I can make one of the parts I or J deeper at its inner 35 end and pivot the wire K to the upper portion of the deepened part, while the lower portion is pivoted to the other arm of the toggle. This may practically cause the wire to give its effect exactly at the central knuckle.

Fig. 5 shows such a construction.

I claim as my invention—

1. In a piano, keys each arranged to be depressed to an invariable extent, and provisions for limiting the extent of motion of the 40 corresponding hammers, in combination with a series of tongues serving leverwise between the keys and the hammers, and with provi-

sions comprising the series of links E, lost-motion rod G, toggle-piece J and operating wire or rod K, for shifting the leverage of the 45 whole series to correspondingly vary the extent of the movement and avoid lost motion without liability to warping, all substantially as herein specified.

2. In a piano, keys each adapted to be depressed to an invariable extent, and a shifting hammer-rail adapted to limit the extent of motion of the several hammers, in combination with a series of tongues serving leverwise between the keys and the hammers and 55 with provisions comprising the series of links E, lost-motion rod G, hook-links G', springs F, double toggle I J, and operating connection K for shifting the leverage of the whole series by means of a mechanical connection 60 from the soft pedal without liability to warping, all substantially as herein specified.

3. In a piano, keys each adapted to be depressed to an invariable extent and a shifting hammer-rail adapted to limit the extent 65 of motion of the several hammers, in combination with a series of tongues serving leverwise between the keys and hammers and with a pendent link E for each tongue, a movable lost-motion rod extending transversely of the 70 piano engaged with capacity for easy disengagement with the series of links, and means connected with the soft pedal through the hammer-rail D, screw K and toggle I J, arranged for joint operation substantially as 75 herein specified.

In testimony that I claim the invention above set forth I affix my signature in presence of two witnesses.

AUGUST RICHTER.
